UNITED STATES PATENT OFFICE.

CHARLES H. WASHBURN, OF NEW YORK, N. Y.

AUTOMATIC STEERING APPARATUS.

SPECIFICATION forming part of Letters Patent No. 313,901, dated March 17, 1885.

Application filed July 21, 1884. (No model.)

To all whom it may concern:

Be it known that I, CHARLES H. WASHBURN, a citizen of the United States, and a resident of New York, in the county of New York and State of New York, have invented 5 certain new and useful Improvements in Automatic Steering Apparatus, of which the following is a specification.

My invention relates especially to means 10 and mechanism for operating the rudder upon vessels, and has for its object the provision of an apparatus cheap and simple to construct, easy to use, and which shall be instantaneous, effective, and certain in operation.

15 To attain the desired end my invention consists, essentially, in the combination, with a cylinder having communication with a compressed - air supply, a piston playing in said cylinder operating the tiller-wheel chains, of 20 a main rotary valve of peculiar construction, by which the air-supply to the cylinder is regulated. This main valve is adapted and arranged to be operated by an auxiliary cylinder and valve, regulated by electro-magnets, 25 said magnets being actuated by a current controlled by the movement of the needle of a mariner's compass. This compass consists of the ordinary bowl supported in the usual manner, and containing a balanced card. Sup- 30 ported above the card is a rocking-bar, properly insulated, and having an arm extending horizontally from each side. Depending from each arm is a swinging rod, having a flexible termination formed of links. Secured to the 35 supporting frame, at each side thereof beneath the said links, are curved plates. The said plates and rocking - bar are electrically connected with the above-mentioned magnets for operating the auxiliary valve, a suitable bat- 40 tery being located in said circuit. In addition to the main automatic valve operated by the auxiliary valve, cylinder, and the compass, a second valve, placed in the air-supply to the cylinder, is so arranged as to be operated by 45 means of electro-magnets, the circuits thereof being controlled by the movement of the wheel in the pilot-house, or by a hand device upon the bridge. Said circuits are so arranged that when the automatic device is in operation the 50 circuit of the hand-devices will be broken, and when either of the hand devices is in

use the automatic circuit will be broken; and my invention also involves certain other novel and useful combinations or arrangements of parts, and peculiarities of construction and 55 operation, all of which will be hereinafter first fully described, and then pointed out in the claims.

In the drawings, Figure 1 is a plan and partial section of the pneumatic cylinder and the 60 valves for controlling the movement of the piston actuating the tiller-wheel chains. Fig. 2 is a view in elevation of my improved valve-shell, the valve-blade being indicated by the dotted lines. Fig. 3 is a plan view of my im- 65 proved mariner's compass. Fig. 4 is a vertical sectional view thereof at line xx of Fig. 3. Fig. 5 is an enlarged perspective view of the rocking bar and supporting-frame forming a part of the mechanism of the compass. Fig. 70 6 is a view in elevation of the wheel in the pilot-house. Fig. 7 is a plan view of the hand-steering device placed upon the bridge. Fig. 8 is a vertical sectional view of the low-pressure alarm attached to the compressed-air res- 75 ervoir, forming a part of my system. Fig. 9 is a view in elevation of a tell - tale compass made in accordance with my invention, and placed in the captain's cabin. Fig. 10 is a plan view of a portion of the deck of a vessel 80 whereon my apparatus is employed, the location and arrangement of the various parts of the device being clearly indicated.

Like numerals of reference, wherever they occur, indicate corresponding parts in all the 85 figures.

1 is a metallic cylinder of the requisite length, wherein plays a piston, 2, having a double rod, 3, extending through a stuffing-box, 4, in each head of the cylinder. This 90 piston is designed to be actuated by compressed air. The ports 5 are placed at each extremity of the cylinder in the usual manner, but at the bottom side thereof, so that any foreign substance finding its way into the 95 cylinder will be carried therefrom as soon as the exhaust at that side of the piston is in operation. The extremities of the piston-rods are united to the tiller-wheel chains 6, which 100 pass around suitable sheaves, 7, to the quadrant-wheel 8, secured to the rudder-head, as plainly indicated in Fig. 10.

9 is an air-supply pipe leading from a reservoir, 10, the air being carried thereto from a compressor, 11. (Indicated by the dotted lines in Fig. 10.) The exhaust 12 is carried from the valves to the stoke-hole, or any point in the vessel where a current of air may be desired.

The main valve used in the automatic circuit is shown in detail at the bottom of Fig. 1. 13 is the valve-shell, and 14 the blade, supported vertically therein by the valve-stem 15 at top, and a continuation, 16, thereof at bottom. Stem 15 passes through a suitable stuffing-box, 17, and bears an operating-lever, 18. 19 are the pipes leading from the valve-shell to the cylinder-ports. Attached to each side of the lever 18 are chains 20, which engage with rods 21, bearing buttons or stops 22. 23 are springs coiled around rods 21. By this construction, when the lever is thrown to the right or left, the spring upon the opposite side will be compressed, permitting the chain to drop. The button or stop at the extremity of the released chain prevents the action of the spring thereto attached, and thus the tendency of the spring is to always return the valve to the position indicated in Fig. 1, when no pressure is exerted upon lever 18.

24 is an auxiliary cylinder wherein plays a piston, 25, the rod 26 thereof engaging with an extension pivoted thereto and to the valve-lever 18 of the main automatic valve. The auxiliary valve is constructed as before explained, with the exception of one extremity of the blade. In this said valve the extremity of the blade 14, next to the exhaust-port, is cut away on each side at an angle one-third of its thickness, as indicated in Fig. 1. The operating-lever 18 of the auxiliary valve is so arranged as to be acted upon by electro-magnets 27 and 28, the tendency of the springs 23 being to maintain it normally in a central position between the magnets. Conductor 29 is connected with one pole of a battery, 31, and conductors 30 to the other pole. These circuits are arranged to be automatically made and broken by means of my improved compass attachment.

30 In the compass 32 is the bowl, supported in the usual manner. Upon the inner side of the rim of the bowl is formed a circumferential sleeve, groove, or channel, 33, wherein is supported an annular toothed plate, 34.

35 is a gear-wheel journaled upon the rim of the bowl, the shaft 37, whereon said wheel is mounted, being provided with an operating-button, 36.

38 is the compass-card balanced in the usual manner upon a pin, 39, extending from the bottom of the bowl.

40 is a frame attached to plate 34.

41 is a rocking bar supported in bearings 42, made of agate or similar material, a set-screw, 43, regulating the pressure of said bearings.

Extending from bar 41 are arms 44 and 55,

each of said arms supporting a suspended rod, 45, provided at its lower extremity with several links, 46.

70 A vertical pin, 47, made of insulating material, extends from bar 41 to card 38, and through a perforation, 48, therein, and a rigid vertical bar, 49, made of insulating material, extends from frame 40 through a slot, 50, in 75 said card.

51 are curved conducting plates adjustably supported beneath frame 40, electrically insulated therefrom. The conductors of the circuits of the magnets 27 and 28 are one to each 80 plate 51, and the other to the rocking bar 41, through a perforation in the bowl of the compass, said conductors being properly insulated from each other and passing around the interior of the bowl, as indicated in Fig. 4. 85

52 is a pin attached to plate 34, extending downward between the edge of the bowl and the compass-card. 53 is a second pin extending horizontally from a sliding strip, 54, mounted upon the interior of the bowl, as shown in 90 Fig. 4.

When constructed and arranged in accordance with the above description, the operation of my automatic device is as follows: With the various parts in the position shown in 95 Fig. 1, the rudder is held at "steady." The direction it is desired to steer being determined, the needle of the automatic compass is set in the proper position by turning plate 34 to the right or left, the compass-card being 100 carried around by the bar 49, extending through the slot 50 therein, and when the vessel is on the desired course the mechanism upon the compass should be in such a position as is shown in Fig. 3, bar 49 occupying the center of 105 slot 50. Should the vessel fall off to starboard the card 38 will remain stationary, but as the bowl is turned to the right the pin 47 will cause the rocking bar to partially revolve, depressing the arm 55, dropping pendant 46 110 against the curved plate therebeneath, completing the circuit to magnet 27, drawing the lever of the auxiliary valve to the right, instantly opening said valve and permitting the compressed air to force piston 24 to the right, 115 opening the main automatic valve, admitting air to the port side of the main cylinder, porting the helm. The instant the vessel answers the rudder and returns to her course the contact between the flexible pendant and the plate 120 51 upon the compass will be broken by the return of the card to its normal position, bringing the arms upon the rocking bar up horizontally, breaking the magnet-circuit. The springs upon the lever of the auxiliary valve 125 instantly center the blade, and the air exhausts from cylinder 24.

By beveling the blade at the exhaust-port, as before explained, the valve will exhaust with great rapidity, as when said blade is 130 turned so as to close the supply-port the exhaust-port is one-third open in each direction, and is wide open when the supply-port is but two-thirds open. Thus there is no resistance

offered to the instant action of the piston of the auxiliary cylinder, and such action is rendered immediate. As the auxiliary valve and piston return to their normal position, the 5 springs upon the main automatic valve will instantly center the blade, locking the piston-head of the main cylinder in whatever position it may have attained.

Should the vessel fall off to port, the circuit 10 of magnet 28 will be closed, and the above-described operation will be repeated, but opening the valves in the opposite direction, bringing the rudder to starboard.

The plate 34 may be turned from the position shown in Fig. 4 around one nearly complete revolution until pin 52 strikes pin 53 upon slide 54, when said slide will permit the plate to travel about one-half an inch beyond a complete circle. By this means every 20 degree may be reached by the needle, and danger of twisting or severing the conducting-wires upon the interior of the bowl will be obviated, the loop shown providing for over a full turn of the plate in either direction.

25 It will be observed that the contact-plates 51 are curved. This curve follows the periphery of the circle which is made by the extremities of the arms upon the rocking bar and the pendants therefrom. Consequently, 30 no matter how far the pendant may travel down the plate, the contact will remain the same between said pendant and plate, and the advantages of a sliding frictional contact are obtained and the balance of the rocking bar 35 maintained, reaction upon the compass-card being prevented.

The compass-card, when set, can turn only so far as is permitted by the bar 49, extending through slot 50. Consequently, the pin 47, 40 extending from the rocking bar, can never be withdrawn from the card, and all danger of disarrangement of the mechanism of the device is obviated. That portion of the said mechanism supported above the card, operated by the 45 deflections of the needle, requires so little power to move it that the resistance does not retard the movement of the needle in an appreciable degree.

In addition to the main automatic valve for 50 operating the main cylinder of my apparatus, a second valve, preferably located upon the opposite side of the cylinder, is employed, the same being fully illustrated in Fig. 1. The valve and shell are constructed and arranged 55 as before described; but, instead of the lever 18, a toothed wheel, 56, is secured to the valve-stem. Pivoted to the valve-stem is a bar or rod, 57, the free extremity thereof extending between two electro-magnets, 58 and 59. Projecting from bar 57, at an angle upon each 60 side, are two adjustable pawls, 60, pivoted to said bar at 61, the angle of divergence of the pawls being regulated by set-screws 62, springs 63 forcing said pawls against the teeth upon wheel 56. Rod or bar 57 engages with chains 20, controlled by springs 23, as before described for the other valves.

64 is one conductor of the magnet-circuits, and 65 are the other conductors.

66 is the wheel located in the pilot-house, 70 the king-spoke 67 thereof showing when the main valve is closed. Affixed to the wheel are a series of projections, 68, or an uneven surface, said projections corresponding in number to the teeth upon valve-wheel 56. Pivoted 75 below said series of projections is a bifurcated lever, 69, said lever being electrically connected with conductor 64 and normally held in an upright position by springs 92. 70 are springs secured in such a position that the arms 80 of lever 69 may press against one or the other when thrown to the right or left. Springs 70 are in electrical connection with conductors 65. 71 and 72 are insulated metallic springs electrically connected with the conductor of the 85 automatic circuit, said circuit being through contact-points 73. Spring 72 extends to a notch, 74, upon the wheel. An elongated button, 75, is placed between springs 71 and 72, as shown, for the purpose of breaking the connection therebetween, and maintaining the break when required.

When it is desired to control the rudder from the pilot-house, by turning the wheel to the right or left the point of the spring 72 95 will be depressed, breaking the automatic circuit of the auxiliary-valve magnets. The lever 69 will be thrown to the right or left by the projections 68, completing the circuit of either magnet 58 or 59, as may be required. Each 100 electric impulse will turn wheel 56 one notch, and by turning wheel 66 one-eighth of a revolution the necessary number of impulses will be given to open the valve wide, putting the helm hard down. As each projection 105 completes the circuit and turns the wheel 56 one notch, the rudder may be readily placed in any position. By turning the wheel back to the position shown in the figure the piston will be locked in position and the automatic 110 circuit resumes operation, as will be readily understood.

If it is desired to cut out the automatic circuit for a period of time, contact between springs 71 and 72 may be permanently broken 115 by means of button 75.

76 is a hand device located upon the bridge or other preferred part of the vessel for operating the steering apparatus, the electric circuit thereof being the same as that next above 120 described.

In addition to the mechanism for breaking the automatic circuit, the circuit of wheel 66 is cut out by means of springs 77 and 78. Conductor 64 leads from the lever 69 to spring 125 77, and spring 78 is supported above spring 72, and is arranged to be operated thereby, but is insulated therefrom. When the hand device 76 is turned, spring 72 is raised by the forcing of its point from the notch 74, breaking both connections, or by turning the button 75 the same result will be obtained. The operation of this device in connection with the hand-valve is independent of both the

wheel in the pilot-house and the automatic device, and neither of these can be used while the hand device is in use. This will enable the officer upon the bridge to assume control 5 of the ship instanter, whenever occasion may require.

If desired, suitable valves may be located in each of the air-pipes 19, connected with the cylinder, in order to shut off either of the 10 valves connected therewith, if desired.

I have found it necessary that the air-pressure should not vary. The high-pressure degree is regulated by the compressor upon the well-known principle; but to guard against the 15 pressure falling too low, I have designed an alarm for use in connection with my apparatus, the same being shown in Fig. 8. 79 is a valve-shell screwed into the air-tank 10. The valve 80 is provided with a stem, 81, which 20 extends through a chamber, 82, upon the top of the valve. A spring, 83, regulated by a nut, 84, governs the pressure at which the valve will fall. 85 is a packing-ring encircling the valve-stem within box 82. When in the position 25 shown in Fig. 8, this ring rests against the top of the box; but when pressure upon the valve is removed, it rests upon the bottom of said box, preventing an undue escape of air. 86 and 87 are insulated contact-points 30 electrically connected with an alarm-bell, 88, located in the engine-room. When the pressure in the reservoir falls below the predetermined standard, the valve drops, completing the circuit of bell 88, notifying the engineer 35 to increase the pressure, and as it rises to the desired point the circuit will be broken, as plainly shown.

Fig. 9 shows a compass constructed in accordance with my invention, as above described, which is placed in the captain's cabin 40 to act as a tell-tale. Instead of being located in the steering-circuit it has electrical connection with an alarm-bell, 89. It is covered by a transparent canopy, 90. When the automatic compass is set upon the proper course, 45 the tell-tale is set to tally therewith, but permits a deviation slightly in excess of that of the compass controlling the steering-circuit. In case of variation beyond the point described 50 the bell-circuit will be closed, notifying the captain of such deviation.

The advantages of my improved apparatus may be summed up as follows: In addition to the ordinary hand-steering apparatus I place 55 upon each vessel an automatic system complete in itself, which will govern the movement of the vessel with absolute accuracy and the utmost dispatch. A system independent of the automatic device is arranged for use in the 60 pilot-house, and a third, independent of each of the above, is located upon the bridge. By my arrangement only one of the systems can be operated at a time. The mechanism is simple, not liable to get out of order, and silent 65 in operation. By my peculiar arrangement of the compass the current of electricity employed therewith will not affect the needle.

The ship is under the instant control of the chief officer on duty, the alarm in the engine-room and the tell-tale in the captain's cabin 70 providing amply for the safety of life and property in any emergency that may arise, and time is economized in the voyage, and the disagreeable and unreliable features of other systems of steering now extant are dispensed with. 75

I am aware of the existence of Patent No. 198,126, issued December 11, 1877, to Lay, and that to Ballard, No. 107,326, dated September 13, 1870, for boat-steering appliances, and to the construction of the devices therein 80 shown and described I make no claim.

Having now fully described my invention, what I claim as new therein, and desire to secure by Letters Patent, is—

1. In a steering apparatus, the combination, 85 with a pneumatic cylinder wherein is located a piston the rods whereof control the movement of the rudder, of a main valve the blade whereof is actuated by an auxiliary piston, cylinder, and valve electrically controlled, 90 substantially as shown and described.

2. The combination, with a rotary valve of the character herein specified, of a self centering and locking device consisting of a flexible cord or chain engaging with the operating-lever of the valve and with springs 95 each side thereof, substantially as shown and described.

3. The herein-described self-centering device for rotary valves, consisting of flexible 100 cords or chains engaging with the operating-lever and with controlling-springs, the action of said springs being controlled by stops or buttons, substantially as shown and described.

4. In an electrical steering device of the 105 character herein specified, a four-way valve provided with a self-centering valve-blade, whereby the piston controlling the movement of the rudder may be locked in place, substantially as shown and described. 110

5. A valve consisting of a shell, 13, having four ports, as set forth, the rotating blade 14 being provided with an operating-lever, 18, said lever engaging with chains 20, whereon are fixed stops or buttons 22, springs 23, engaging with the extremities of the chains opposite to the operating-lever, substantially as 115 and for the uses and purposes shown and described.

6. In an electric steering apparatus of the 120 character herein specified, the combination of the main valve, cylinder, and piston controlling the movement of the rudder, with an auxiliary cylinder and electrically controlled valve the blade whereof is cut away, substantially as set forth. 125

7. In a steering apparatus of the character herein specified, the combination, with a main cylinder and a piston operated by a main valve, auxiliary piston, cylinder, and auxiliary valve, of electro-magnets, the circuits whereof are controlled by a compass, substantially as shown and described. 130

8. In a compass, the combination, with the

- bowl and pivoted card, of a movable frame, supported thereabove and carrying a rocking bar adapted and arranged to close either of two electric circuits, as set forth.
- 5 9. The combination, with the bowl of a compass, of a circumferential channel wherein is supported a movable plate bearing a frame extending over the card of the compass, said frame supporting a rocking bar provided 10 with arms adapted and arranged to make or break one or more electric circuits, substantially as shown and described.
- 15 10. The combination, with a rocking bar, of arms projecting therefrom and a vertical pin engaging with the compass-card therebeneath, said arms supporting pendants adapted and arranged to make electrical connection with curved conducting-plates supported therebeneath, substantially as shown and described.
- 20 11. In a mariner's compass of the character herein specified, the combination, with the depressible pendants, of the insulated curved metal plates therebeneath, said pendants and plates forming a circuit-maker, substantially 25 as shown and described.
12. In a compass of the character herein specified, the combination, with an annular toothed plate, of an arm projecting downward therefrom and a sliding stop therefor, substantially as shown and described.
- 30 13. In a compass, the combination, with the card, slotted as described, of a bar extending through the slot and carried by an adjustable frame, whereby disarrangement of the parts is 35 prevented, substantially as set forth.
14. A compass adapted and arranged to open or close one or more electric circuits by the deflection of the needle, said compass consisting of a bowl, 32, bearing a circumferential channel, 33, wherein is located a rotatable toothed plate, 34, supporting a frame, 40, wherein is a rocking shaft, 41, having arms 44 and 54, bearing pendants 46, curved insulated plates 51 being supported beneath said pendants, as set forth, a vertical bar, 47, extending 45 through a perforation, 48, in a balanced card, 38, and a vertical pin or bar, 49, extending

from frame 40 through a slot, 50, in said card, the whole arranged to operate substantially as set forth.

15. In a steering apparatus, the combination, with the main cylinder, of a rotary valve bearing a toothed wheel upon its stem, the movements of said valve being governed by pawls engaging with the teeth upon said wheel, 55 said pawls being actuated by electro-magnets, the circuits whereof are controlled from a hand device upon the bridge or in the pilot-house, substantially as shown and described.

16. The combination, with a valve of the character herein specified, of a toothed wheel, 56, mounted upon the stem thereof, bar 57, pawls 60, chains or cords 20, springs 23, and electro-magnets 58 and 59, substantially as 60 shown and described.

17. The combination, with the circuits of the electro-magnets adapted and arranged to regulate the position of a rotary valve, of a bifurcated lever having electrical connection with one conductor, and one or more pins or projections mounted upon a wheel or frame adapted and arranged to close either of said circuits, substantially as shown and described.

18. In an apparatus of the character herein specified, the combination, with a main valve, 75 of a circuit-making lever or wheel and circuit-connections, as described, the whole adapted and arranged to open said valve, driving a piston in one direction when moved, the return movement of said lever or wheel locking 80 the piston in place, substantially as set forth.

19. The combination, in an apparatus of the character herein specified, of a hand apparatus, 76, with a cut-out for the automatic circuit and for the circuit to a wheel, 67, substantially as set forth.

Signed at New York, in the county of New York and State of New York, this 19th day of July, A. D. 1884.

CHARLES H. WASHBURN.
